UNITED STATES PATENT OFFICE.

LUIGI TADDEO, OF CLEVELAND, OHIO.

FOUNTAIN PEN.

Application filed July 20, 1921. Serial No. 486,083.

To all whom it may concern:

Be it known that I, LUIGI TADDEO, a citizen of the United States, resident of Cleveland, county of Cuyahoga, and State of Ohio, have invented new and useful Improvements in Fountain Pens (case C), of which the following is a specification, the principle of the invention being herein explained and the best mode in which I have contemplated applying that principle, so as to distinguish it from other inventions.

My invention relates to improvements in fountain pens. Particularly, the invention relates to a new and improved construction of the plunger utilized for the filling or emptying of the pen. The invention further relates to new and improved means forming a closure or cap for the outer end of the ink reservoir. The invention is an improvement in the construction of fountain pens shown, described and claimed in my U. S. Letters Patent Nos. 1,409,616 and 1,409,617.

The annexed drawing and the following description set forth in detail certain means embodying my invention, the disclosed means, however, constituting but one of the various forms in which the principle of the invention may be employed.

In said annexed drawing:

Figure 1 represents a partial elevation and a partial longitudinal section of my improved fountain pen, showing the ink reservoir of the same empty, the parts of the pen being in those relative positions which they occupy just previously to filling the pen;

Figure 2 is a view similar to Figure 1, showing the parts in the positions which they occupy just after filling the pen;

Figure 3 is a view similar to Figures 1 and 2, showing the pen parts in those relative positions which they occupy when the pen is filled and ready for use;

Figure 4 is a view of a fragmentary part of Figure 1, upon an enlarged scale;

Figures 5 and 6 represent, respectively, top and bottom plan views of the elements shown in Figure 4;

Figure 7 is a view of fragmentary parts of Figure 3, upon an enlarged scale;

Figure 8 is a plan view, upon an enlarged scale, of a brass stamping, forming part of my new and improved plunger, the same being shown in this figure as it appears before

it is formed into the shape which it occupies in the completed plunger;

Figure 9 is a side elevation of the element shown in Figure 8; and

Figure 10 is a side elevation of said brass stamping, showing the same in the form which it assumes in the completed plunger, the plunger body being suggested in dot and dash outline.

Referring to the annexed drawing in which the several parts are indicated by the same ordinals, respectively, in the several views, an ink barrel or reservoir of a fountain pen is indicated by the ordinal 1, the same being secured in any suitable manner to the neck portion 2 of the pen in which the pen proper 2' is secured. The barrel 1 is formed with an ink chamber 3 adapted to be filled by ink 4 drawn in through the neck portion 2 by suction, as is well understood. This suction is created by the operation of a plunger 8 having a plunger rod 5, formed with an outer enlarged operating and cap portion 6, and an inner enlarged head portion 7. By means of a partition wall 10 the barrel 1 is subdivided into two chambers 3 and 9, the partition 10 being formed with an enlarged hole 10' forming a guide for the reciprocations of plunger rod 5. The outer end of the barrel 1 is formed with an internally screw threaded portion 9' adapted to co-operate with an externally screw threaded portion 6' formed upon the cap or closure 6. The inner head 7 of the plunger rod 5 is formed with an externally screw threaded portion 7' adapted to co-operate with an internal thread 13 formed in the body 11 of

a brass stamping, hereinafter more fully described, having a plurality of arms 12 as plainly shown in Figure 8. By reason of the provision of the enlarged hole 10', the plunger rod 5 does not bind when reciprocated and a certain lateral adjustment is allowed to the compressible plunger 8. Also, by the provision of an internally-threaded outer end 9' and the cooperating externally-threaded closure 6' I effectively seal the open end of the ink reservoir to a degree which is not possible when the plunger rod intersects an externally-threaded outer end portion of the ink reservoir which cooperates with an internally-threaded closure member.

The brass stamping 11 is stamped out in the form shown in Figure 8, drilled and

100

105

110

tapped to form the threaded hole 13 and then the arms 12 are bent into parallel positions substantially at right angles to the plane of the body portion 11. This multiple-prong nail member is then driven through the plunger 8 so that the tapped hole 13 is substantially central of the plunger, the prongs 12 being substantially the same length as the depth of the plunger. The free ends of the prongs 12 are then bent in toward each other, as illustrated by 12', Figure 10, whereby the arms 12 are securely clinched within the plunger body 8.

It is evident from the accompanying drawing and the foregoing description that, the pen parts being in the relative positions shown in Figure 3, the pen, however, being considered to be emptied of ink, the head 6 can be conveniently turned by the engagement of the operator's fingers with a frictional surface 6², and said head freed from the barrel 1. This result is plainly shown in Figure 1. Then the plunger rod can be pulled upwardly to the position shown in Figure 2, the barrel 1 being empty, however, when, by a further turning of the rod 5 through the medium of the cap 6, the threaded portion 7' of the rod can be caused to engage the tapped hole 13. Then the plunger rod 5 and plunger 8 can be pushed inwardly into the position shown in Figure 1. Then by pulling the plunger outwardly, the pen will be filled with ink, as plainly shown in Figure 2. Turning the plunger rod 5 will then disengage the threaded portion 7' thereof from the threaded hole 13 so

that the plunger rod can be pushed inwardly through the ink 4 to the position shown in Figure 3. The rod 5 can then be turned to cause the threaded portion 6' of the cap 6 to engage the threaded portion 9' of the barrel 1 effectively to close the outer end of the barrel 1.

I wish particularly to point out that, by the means shown in the accompanying drawing, hereinbefore described and hereinafter claimed, I have provided a very effective plunger at a very nominal cost. The member 8 is made of fiber, or any other suitable compressible material. The member 11 is very economically produced, economically assembled in the member 8 and forms a very effective strengthening or reinforcing member therefor. Also, I wish particularly to point out that the member 6 forms a very effective operating member for the plunger rod and also serves as an effective closure for the barrel.

What I claim is:

A fountain pen comprising a hollow body forming an ink reservoir; a reciprocable plunger therein formed of compressible material; a metal reinforcement for said material having a central body member formed with a tapped hole and a plurality of arms forming prongs driven into said material; and a plunger rod formed with a threaded portion adapted to co-operate with said tapped hole.

Signed by me this 13th day of July, 1921. 70

LUIGI TADDEO.
